UNITED STATES PATENT OFFICE.

FERDINAND LOGAN, OF PHOENIXVILLE, PENNSYLVANIA.

STEAM AND AIR MIXER FOR GAS-GENERATORS.

1,251,252.

Specification of Letters Patent. Patented Dec. 25, 1917.

Application filed June 16, 1916. Serial No. 103,981.

To all whom it may concern:

Be it known that I, FERDINAND LOGAN, a citizen of the United States, residing at Phoenixville, in the county of Chester and State of Pennsylvania, have invented certain new and useful Improvements in Steam and Air Mixers for Gas-Generators, of which the following is a specification.

My invention relates to a steam and air mixer for gas-generating furnaces.

The main object of this invention is to provide a simple, durable, economical and efficient steam and air mixer attachment to a gas-generator, said attachment being so constructed that the steam being retarded in its passage therethrough and in contact therewith causes it to become as intensely hot as the steam will make it, in from three to four minutes, thereby imparting heat to the air fed therethrough in contact therewith and commingled with the steam so that the air becomes as hot as the steam, the said heated air absorbing all moisture from the steam, thus avoiding all condensation in the bottom of the generator.

A further object of the invention is to attach my improved steam and air mixer at one side of a gas-generator near the base portion thereof so that it will supply a combined stream of air and steam under pressure beneath the grate-bars of the generator and cause the same to pass upward through the incandescent body of fuel and become a fixed gas before passing from the generator to the superheater and which cannot become stratified.

Another object of this invention is to so construct my steam and air mixer that a retarding chamber is formed in the bottom portion thereof wherein the air is highly heated, and the steam and air is thoroughly mixed before being discharged beneath the grate-bars of the generator, thereby eliminating all condensation from the bottom of the generator, and thus preventing the deadening of the fire and lessening the heat units at the bottom of the fuel bed within the generator.

The foregoing and such other objects as may appear from the ensuing description are attained by the novel features of construction, combination, arrangement and location of the parts, hereinafter fully described, illustrated in the accompanying drawings, and particularly pointed out in the claims appended hereto, it being under-

stood that slight changes in the form, proportions, and minor details of the construction may be resorted to without departing from the spirit or sacrificing any of the advantages of the invention.

In the accompanying drawings it will be seen that:

Figure 1, is a longitudinal vertical section through the fire-box of the gas generating furnace, illustrating in elevation the application of my improved steam and air mixer thereto, and showing in section the discharge pipe located below the grate of the generator.

Fig. 2, is a vertical section illustrating an enlarged view of my steam and air mixing device detached from the gas-generator.

Fig. 3, is a vertical section taken on the line $x-x$, Fig. 2, and

Fig. 4, is a plan view of the same showing the discharge pipe connected therewith.

Similar numerals of reference are employed to designate corresponding parts throughout the several figures of the drawings.

In carrying out my invention as illustrated and which shows a preferred construction, the gas-generating furnace A, of which the fire-box only is shown, may be of any suitable or desirable construction, and a grate 1, of any desired type may be utilized to support the mass or bed of fuel 2. At a suitable point beneath the grate a discharge or outlet pipe 3 is passed through an opening in the wall of the generator A, the inner end of said pipe terminating within the generator at a point closely adjacent to the opposite wall thereof, as clearly shown in Fig. 1, the upper portion of said pipe 3 having a plurality of longitudinal discharge slots 3', and the outer end of the pipe 3 is rigidly secured to the threaded outlet portion 4 of a casting 5, said casting consisting of an upright hollow body portion 6, having a threaded opening at its upper end 7, adapted to receive and rigidly secure the threaded end portion of an air pipe 8. Near the upper end of the casting at one side thereof is formed a threaded opening in which is fitted a threaded hollow tube or pipe 9, to the outer end of which is rigidly secured one end of an elbow tube or pipe 10, the other end of said elbow being interiorly threaded, and adapted to receive and rigidly secure the threaded end portion of a steam pipe 11, while to the inner end of said tube or pipe 9,

within the upper portion of the casting, is rigidly fitted one threaded end of an elbow tube or pipe 12, and to the other threaded end of the elbow pipe 12 is securely fastened 5 a steam discharge or outlet pipe or nozzle 13. Integral with the said casting at the lower end portion thereof is an annular retarding chamber 14, the walls of which become intensely hot in from three to four 10 minutes by the course of the steam passing therethrough and in contact therewith, the chamber 14 being formed by the interior downwardly extending wall 15, the outer wall 16, and the inner wall 17, the said chamber being provided with an outlet opening 18 formed through the inner wall 17, and leading to the outlet portion 4 of the casting. In the opening formed in the casting at a 15 point directly opposite the said outlet portion 4, is rigidly and securely fitted a screw-threaded plug 19 adapted to close the said opening.

In the operation of this improved steam and air mixer, the steam will be caused to emerge from the nozzle 13 under pressure 25 within the casting, thereby causing an intense suction within said casting, and causing the air to flow through the air pipe 8 into the hollow body portion 6, thence into 30 the retarding chamber, which has become intensely hot by the retardation of the steam passed therethrough, and the air becomes 35 with the highly heated walls of the circular chamber and becomes thoroughly mixed and commingled with the steam, from whence the highly heated combined mixture of air and steam is discharged into the generator 40 through the longitudinal slotted discharge opening 3' formed through the upper portion of the outlet pipe 3, at a suitable point below the grate, and passes upward through the incandescent body of fuel and merges 45 into a fixed gas before passing from the generator to the superheater and which will not stratify.

It will be understood that suitable regulating and relief valves may be utilized in 50 connection with the steam and air supply pipes in order to supply any desirable amount of air or steam, dependent upon the volume and quality of product desired to be generated.

55 In view of the fact, that the retarding chamber is provided with a discharge or outlet opening at each side thereof, it will be readily perceived that either side of the casting may be positioned adjacent to the 60 gas generator, one of the openings being closed with a suitable plug.

It will be obvious that my improved steam and air mixers may be made of different sizes, dependent upon the capacity of the 65 plant, and the quantity of the product de-

sired, and may readily be utilized for the purpose of heating up steam boilers and re-heating gas generators.

Having thus described my invention what I claim and desire to secure by Letters Patent is:—

1. A steam and air mixer for gas-generators attached to a generator at one side thereof and independently of said generator, consisting of a casting having an upper 75 hollow portion, an annular integral retarding chamber forming its lower portion, side walls to the said chamber with openings formed in said walls, and a discharge pipe connected at one end to one of the openings 80 in the side walls of the retarding chamber and the other end terminating within the generator below the grate thereof.

2. A steam and air mixer for gas-generators attached to the generator at one side 85 thereof and independently of said generator, consisting of a casting having an upper hollow portion, and an integral annular retarding chamber formed at its lower portion, side walls to the chamber with openings formed therethrough, said retarding chamber having a discharge opening formed 90 in its inner wall, an opening formed in one of its side walls to which a discharge pipe is secured, and an opening in the other side 95 wall adapted to be closed by a plug.

3. A steam and air mixer for gas-generators attached to the generator at one side thereof and independently of said generator, consisting of a casting having an upper 100 hollow body portion interiorly threaded at its upper end to receive an air pipe, and having a threaded opening formed therethrough near its upper end adapted to receive a steam pipe, a steam pipe outlet 105 fitted within said body portion, and a heated annular retarding chamber forming the lower end of the casting, side walls to the chamber having openings formed therethrough and having a discharge opening in 110 the inner wall of said chamber, an opening in one of the side walls adapted to receive a discharge pipe, and an opening in the other side wall to which a plug is fitted.

4. A steam and air mixer for gas-generators attached to the generator adjacent thereto, consisting of a casting having a hollow portion at one end adapted to receive air and steam, and an integral highly heated retarding chamber at its other end 115 formed by an inner inclined wall, inner and outer annular side walls to the chamber, said inner wall having an outlet formed therethrough, and the outer side wall having an outlet opening at one side to which the discharge pipe is secured, and an opening at 120 the other side which is closed by a plug.

5. A steam and air mixer for gas-generators attached to the generator adjacent thereto, consisting of a casting having a 125

hollow portion at one end adapted to receive air and steam, and an integral highly heated annular retarding chamber at its other end formed by an inner inclined wall, 5 inner and outer annular side walls to the chamber, said inner wall being provided with a discharge opening therethrough, and the outer side walls having an outlet opening at either side, in combination with a 10 discharge pipe connected to one of the side walls of the retarding chamber and terminating in the generator beneath the grate, said pipe having a plurality of longitudinal slotted discharge openings formed there- 15 through, in its upper side.

6. A steam and air mixer for gas generators attached to the generator adjacent thereto, consisting of a casting having a hollow portion at one end thereof adapted

to receive an air pipe and a steam pipe, a 20 steam discharge pipe fitted within said hollow portion, an integral heated retarding chamber forming the other end of the casting, said retarding chamber having inner and outer annular side walls, an inner dis- 25 charge opening formed through its inner wall, and an outer discharge opening at one side, and an opening at the other side to which a plug is fitted, in combination with a discharge pipe one end of the body being 30 fitted to said outer discharge opening in one of the side walls and the other end of the pipe terminating within the generator below the grate, and having a plurality of longitudinal discharge openings formed 35 therethrough in its upper side.
